CONVEYER UNLOADER

Vincent A. Rayburn and Duer C. Robson, Baltimore, Md., assignors to Western Electric Company, Incorporated, New York, N. Y., a corporation of New York

Application December 21, 1945, Serial No. 636,404

5 Claims. (Cl. 214—60)

1

This invention relates to conveyers, and more particularly to conveyers for transporting reels.

In the operation of machines for making articles from wire, large numbers of reels of wires must be transported to the machines. For the greatest ease in the operation of such machines, reserve supplies of the reels of wire must be positioned at an easily accessible location relative to the machines. However, heavy reels are difficult to move and require large amounts of labor to transport them to positions conveniently located with respect to the machines.

An object of the invention is to provide new and improved conveyers.

A conveyer constituting one embodiment of the invention comprises an article-transporting element, means for moving the article-transporting element along a predetermined path, means positioned adjacent to said path for loading articles on said element, and means positioned adjacent to said path for unloading articles from the article-transporting element.

A complete understanding of the invention may be obtained from the following detailed description of a conveyer forming a specific embodiment thereof, when read in conjunction with the appended drawings, in which

Fig. 1 is a top plan view of a conveyer forming one embodiment of the invention;

Fig. 2 is an enlarged, fragmentary, vertical section taken along line 2—2 of Fig. 1;

Fig. 3 is an enlarged, fragmentary, vertical section similar to Fig. 2;

Fig. 4 is an enlarged, fragmentary, vertical section taken along line 4—4 of Fig. 2;

Fig. 5 is an enlarged, fragmentary, vertical section of the conveyer similar to Fig. 4 showing some of the parts in different positions, and

Fig. 6 is an enlarged, fragmentary, vertical section somewhat similar to Fig. 4 showing a portion of a conveyer forming an alternative embodiment of the invention.

Referring now in detail to the drawings there is shown therein a conveyer, which includes a loader 11 and tracks 12—12 serving to guide an endless roller chain 15. The chain 15 is advanced between the tracks 12—12 by a sprocket 16 past the loader 11 and unloaders 20, 21 and 22 to serve machines 25, 26 and 27 positioned adjacent to the unloaders 20, 21 and 22, respectively.

Each of a plurality of hook assemblies 28—28 (Fig. 1) includes a hook 30. A pair of trip rolls 45—45 is carried by the chain at a point a predetermined distance in advance of the hook assembly and precedes the hook as the chain 15 carries the hook beneath the tracks 12—12.

When one of the hook assemblies 28—28 is advanced toward the loader 11 with the hook 30 thereof empty, the trip rolls 45—45 actuate the loader to load a reel on the hook. The reels are

2

advanced to the loader 11 on a loading ramp 80.

The hook assemblies 28—28 are advanced one at a time from the loader 11 past a turner 132 (Fig. 1). The construction of the hook assemblies 5 and the turner is disclosed and claimed in copending application Serial No. 636,401, filed December 21, 1945, now Patent 2,471,347, issued May 24, 1949.

After the hooks 30—30 have been turned by the turner 132 (Fig. 1) so that they point in directions opposite to those in which they are advanced by the conveyer chain 15, the hook assemblies are advanced one at a time past the unloader 20 and the trip rolls 45—45 engage cams of which a cam 166 is shown and move these cams from their full-line positions, as shown in Fig. 2, to their broken-line positions. The cams 166—166 are rigidly fastened to a shaft 170 mounted on a bracket 171 and serve to rotate the shaft 170 in counterclockwise direction, as viewed in Fig. 2, when they are 20 moved from their full-line positions to their broken-line positions, whereby an arm 172 rigidly mounted on the shaft 170 is moved from its full-line position to its broken-line position.

When the arm 172 is rotated from its full-line position to its broken-line position, it moves a link 175 connected thereto downwardly, as viewed in Fig. 2, so that an arm 176 is rotated in a clockwise direction. The arm 176 is connected rigidly to a driving clutch member 177 (Figs. 2 and 4) rotatably mounted on a shaft 181. The driving clutch member normally engages a driven clutch member 180 (Fig. 4) splined to the shaft 181, and if engaged therewith, rotates the driven clutch member and the shaft in a clockwise direction, as viewed in Fig. 2, when the driving clutch member 177 is rotated. The shaft 181 serves to rotate arms 182—182 (Figs. 2 and 4), which raise a table 185, which is pivotally connected thereto and to arms, of 35 which an arm 186 (Fig. 3) is shown, connected to a bracket 187. The arms 186—186 are rotated from their positions shown in Fig. 2 to their positions shown in Fig. 3 when the arms 182—182 are rotated by the shaft 181 from their positions 40 shown in Fig. 2 to their positions shown in Fig. 3, whereby the table 185 is raised. The arms 182—182 are the same length as and are parallel with the arms 186—186 so that they form a pantograph linkage with the table 185 and support the table 185 in a horizontal position regardless of the positions of the arms 182—182 and 45 186—186.

As the table 185 is raised, it raises a concave receiving platform 190 (Fig. 4) from its full-line 55 position shown in Fig. 4 to its broken-line position. The receiving platform 190 is pivotally secured to the table 185 and is tilted by a stop 195 downwardly toward the right when the table 185 is in its full-line position. However, as the 60 table 185 is raised from its full-line position to

its broken-line position, a leg 192 depending from the under side of the platform 190 engages the table, whereby the platform 190 is held in a horizontal position.

When the table 185 is moved from the full-line position shown in Fig. 4, to its broken-line position, the receiving platform 190 engages, lifts and holds the reel 165 from the hook 39. A stop 191 positioned on the platform 190 serves to retard the advancement of reel 165, and as the hook assembly 28 continues to move to the right, as viewed in Fig. 3, the reel 165 is stripped from the hook 39. After the hook has been withdrawn from the reel 165, the trip roll 45 (Fig. 2) is advanced out of engagement with an elongated dwell portion 167 of the cam 166, and the weight of the reel together with the weight of the cam 166 forces the platform 190 and the table 185 to their full-line positions shown in Fig. 4.

As the table 185 and the platform 190 are lowered from their broken-line positions shown in Fig. 4 to their full-line positions, the left side of the platform 190 engages the stop 195 and the platform 190 tilts downwardly and to the right. The reel 165 then rolls from the receiving platform 190 onto a ramp 196 and engages a cam portion 197 (Figs. 2 and 5) of a rider 200 and raises the cam portion 197. The rider 200 is pivoted freely on a rod 205 secured to levers 291-291, which are mounted pivotally on a rod 206. A cam portion 202 of the rider 200 rests on a reel 208 previously unloaded onto the ramp 196, which is filled by the arrival of the reel 165 thereon. Thus, when the reel 165 engages the cam portion 197 of the rider 200, the rider is raised from its position shown in Fig. 4 to its position shown in Fig. 5, whereby the rod 205 is raised and raises a link 207 connected thereto. When the link 207 is raised, it pivots an arm 210 in a counterclockwise direction, as viewed in Fig. 5, whereby a shaft 211 and a yoke 212 connected to the driven clutch member 180 are rotated in a counterclockwise direction. When the yoke 212 is so rotated, it moves the driven clutch member 180 out of engagement with the driving clutch member 177. Consequently, when the chute 196 is filled and a hook assembly following the hook assembly just unloaded approaches the unloader 20, the receiving platform 190 will not be raised when the cams 166-166 (Fig. 2) are actuated by trip rolls associated with that hook assembly, and reels carried thereby will not be stripped therefrom. Hence, overloading of the ramp 196 is prevented.

If the portion of the ramp 196 occupied by the reel 208 had been vacant when the reel 165 was discharged onto the ramp 196, the rider 200 would merely rock on the rod 205 because a recess 209 of the rider would provide clearance for the reel 165 so that the rider as a whole would not be raised and would not raise the rod 205 when engaged by the reel 165 rolling down the ramp 196. Thus, the driven clutch member 180 normally remains in engagement with the driving clutch member 177 until the ramp 196 is filled. The rider 200 and the elements associated therewith do not impede the movement of the reels on the ramp 196 but prevent the operation of the unloader 20 when the ramp 196 is filled.

A pair of L-shaped escapement levers 216-216 (Figs. 1 and 4) are rotatably mounted on posts 217-217 projecting from curbs of the ramp 196, and cam portions 215-215 of the levers 216-216 are urged inwardly over the ramp toward each other by torsion springs 218-218 mounted on the

posts 217-217. A reel 220 engaging a stop 219 (Fig. 4) positioned at the bottom of the chute 196 engages the cam portions 215-215 of the levers 216-216 and thrusts them outwardly away from each other, whereby curved pins 221-221 extending inwardly from the upper ends of the levers 216-216 are maintained in the path of a reel 222 and keep the reel 222 out of contact with the reel 220. A pair of escapement levers 225-225 (Fig. 1), which are identical with the levers 216-216, are held in positions in which they stop another reel (not shown) in a position just above the reel 222, and a reel 226 and the reel 208 are similarly held by levers illustrated by levers 228 and 229, respectively. Thus, all of the reels positioned on the ramp 196 are held from contact with each other.

When an operator of the machine 25 lifts the reel 220 from the chute 196, the torsion spring 218-218 mounted on the pins 217-217 (Fig. 1) and the force exerted by the reel 222 on the curved pins 221-221 thrusts the pins 221-221 apart, and the reel 222 then rolls down the ramp 196 to the position in which the reel 220 is shown. The other reels then move down the ramp one at a time in a similar fashion but are kept out of contact with each other by the levers 216-216 and the pins 221-221 and the levers and pins identical therewith. When the reel 165 moves to the position in which the reel 208 is shown, the cam portion 197 (Figs. 2 and 5) of the rider 200 is freed and the driven clutch member 180 moves back into operative engagement with the driving clutch member 177. Thus, when the next hook assembly is advanced over the receiving platform 190, the platform is raised and unloads a reel therefrom.

As described hereinabove, when the ramp 196 is filled, the receiving platform 190 cannot be raised by trip rolls 45-45 associated with hook assemblies 28-28 advanced therewith as the trip rolls are moved into engagement with the cams 166-166, and the reels carried by the hook assemblies will not be discharged onto the ramp 196. The reels on the hook assemblies, after the ramp 196 is filled, are unloaded by the unloader 21 onto a ramp 230 if the ramp 230 is not filled. If both the ramps 196 and 230 are filled, reels carried therewith by the hook assemblies are discharged by the unloader 22 into a ramp 231 provided the ramp 231 is not filled. If all the ramps 196, 230 and 231 are filled, the reels will be carried by the hooks until a reel in one of the ramps is taken therefrom to render operative the unloader associated therewith.

If it is necessary to withdraw the unloader 20 from the operation of the conveyer system described hereinabove, the table 185 and the levers 182-182 and 186-186 are swung through slightly less than 180° in a clockwise direction, as viewed in Fig. 2, to a position in which the table rests on the ears 187-187. This rotates a tooth 240 (Fig. 4) on the driven clutch member 180 almost 180° out of mesh with a tooth 241 on the driving clutch member 177. The tooth 240 is the only tooth on the clutch member 180, and the tooth 241 is the only tooth on the clutch member 177 and because of this and the fact that the rotation of the driving clutch member 177 is much less than 180° when the cams 166-166 are rotated by the trip rolls 45-45, the tooth 241 does not engage the tooth 240 when the cams 166-166 are engaged by the trip rolls so that no rotation of the driven clutch member 180 is caused. Hence, no unloading by the unloader 20

occurs. The unloaders 21 and 22 may be rendered inoperative in a similar manner if it is so desired.

A turner 227 (Fig. 1) positioned in advance of the unloader 22 is identical with the turner 132, and serves to turn through 180° the hooks 30—30 as the hooks are advanced therewith so that the hooks point in the direction in which they are advanced as they approach the loader 11.

Operation

In the operation of the conveyer described hereinabove, the hook assemblies 28—28 are advanced over the loader 11, which serves to load reels on the hooks 30—30 thereof which are empty, but does not affect hooks already carrying reels therewith. The hooks are then turned 180° by the turner 132 and are advanced toward the unloader 20.

If the unloader 20 is not filled with reels, the receiving platform 190 strips the reels from the hooks 30—30 carrying them and deposits them on the ramp 196. This continues until the ramp 196 is filled with reels, at which time the receiving platform 190 will not be actuated as a hook is advanced therewith. The ramps 230 and 231 are filled successively with reels, whereby the unloaders 21 and 22 do not discharge reels thereon, and, after all of the hooks carried by the chain 15 are filled with reels by the loader 11, the loader does not raise any more reels in the path thereof, until a reel is taken from one of the ramps 196, 230 and 231 so that an emptied hook approaches the loader 11.

The conveyer serves to maintain the ramps 196, 230 and 231 full of reels so that the machines 25, 26 and 27 need not be stopped for lack of reels. Any collision between a reel and another reel or a portion of the conveyer is prevented while the reels are handled by the conveyer.

Alternative embodiment (Fig. 6)

An alternative embodiment of the invention for conveying box-like articles shown in Fig. 6 is similar to the first-described embodiment of the invention except that forked hooks 330—330 provided with bottom tines 331—331 replace the hooks illustrated by the hooks 30—30. Receiving platforms, of which a receiving platform 390 is shown, storage chutes, of which a storage chute 396 is shown, and riders, of which a rider 300 is shown, are substituted for corresponding elements of the first-described embodiment.

A box-like article 371 (Fig. 6) is shown as it is about to be unloaded by an unloader 320 from one of the forked hooks 330—330 as the forked hook is advanced past the unloader 320. As the forked hook is advanced over the receiving platform 390 of the unloader 320, a table 385, to which the right side, as viewed in Fig. 6, of the receiving platform 390 is pivotally secured, is raised by means (not shown) identical with the means described hereinabove for raising the table 185 (Fig. 4). As the table 385 (Fig. 6) is raised, it raises a brake shoe 386 having grooves 387—387, which receive rolls 388—388 in close fitting engagement therewith. Coverings 389—389 of the rolls 388—388 are composed of a rubber compound or other material having a relatively high coefficient of friction so that the rolls 388—388 are prevented from rolling by friction between the brake shoe and the coverings of the rolls. The receiving platform 390 is raised farther and the rolls 388—388 enter between and lift the article 371 from the tines 331—331, which are ad-

vanced out from under the article. At this time, the coverings 389—389 of the rolls prevent the article from moving relative to the rolls because of the friction therebetween.

- 5 After the forked hook 330 is advanced beyond the receiving platform 390, the table 385, the brake shoe 386, the receiving platform 390 and the article 371 lower by gravity. The left end, as viewed in Fig. 6, of the receiving platform 390 strikes a stop 395, and as the table 385, the brake shoe 386 and the right end of the receiving platform 390 continue to descend, the receiving platform tilts downwardly to the right and the brake shoe moves out of engagement with the rolls 388—388. The rolls 388—388 then are free to rotate and the box-like article rolls off of the receiving platform onto and down the storage chute 396.

- 10 The rider 300 having lobes 397 and 402 positioned in the path of the box-like articles is raised when the chute 396 is filled so that two articles engage the lobes 397 and 402. When this occurs, the rider 300 renders the unloader 320 inoperative by means (not shown) identical with those by which the rider 200 (Fig. 4) renders the unloader 20 inoperative. However, a recess 409 provides clearance for articles moving down the chute 396 so that the rider 300 only rocks when the chute 396 is not filled.

Operation of alternative embodiment

In the operation of the last-described conveyer, a suitable loader (not shown) loads box-like articles illustrated by the article 371 on the forked hooks 330—330 and the forked hooks are advanced past the loader with the tines 331—331 thereof pointed in the direction of travel. U-shaped guard rails 309—309 of the forked hooks aid in holding the articles against side-wise movement on the forked hooks. Before the forked hooks reach unloader 320, they are turned to positions in which the tines thereof point opposite to the direction of travel. The receiving platform 390 takes one at a time the articles from the forked hooks and deposits the articles on the chute 396. Before the unloaded forked hooks reach the loader 311 again, each is turned so that it points in the direction of travel to be in position to pick up another article.

45 The above-described conveyers effectively load, convey, unload and store articles of different types entirely automatically and without fouling of the articles or elements thereof. The articles are handled gently but positively and surely throughout their handling by the conveyers.

50 What is claimed is:

- 55 1. In a conveyer, means for carrying an article, means for advancing the article-carrying means along a predetermined path, a receiving platform, a ramp positioned at a point adjacent to said path, a plate for supporting the receiving platform, a bracket for securing one edge of the receiving platform pivotally to the plate, a hoist 60 for mounting the plate in a position in which the receiving platform is below the path of the article when the hoist is at rest, means for actuating the hoist, said hoist serving to move the receiving platform upwardly into the path of the article when actuated so that the receiving platform lifts the article from the article-carrying means, and a stop for engaging the edge of the receiving platform opposite to the edge secured to the plate to tilt the receiving platform as it is lowered.

2. In a conveyer, a hook for carrying a reel, means for advancing the hook along a predetermined path, a ramp positioned at a point adjacent to said path, a receiving platform adjacent to the ramp, a pantograph linkage including a plate for supporting the receiving platform, a bracket for securing one edge of the receiving platform pivotally to the plate, means for mounting the pantograph linkage in a position in which the receiving platform is below the path of the reel when the pantograph linkage is at rest, means for actuating the pantograph linkage to move the receiving platform upwardly into the path of and in the direction of travel of a reel carried by the hook so that the receiving platform lifts the reel from the hook and slides the reel from the hook, said actuating means permitting the receiving platform and the pantograph linkage to lower by gravity after the reel has been slid from the hook, and a stop for engaging the edge of the receiving platform opposite to the edge secured to the plate to tilt the receiving platform as it is lowered, whereby the reel is rolled off the receiving platform onto the ramp.

3. In a conveyer, a platform, a hook for carrying a reel, a chain for advancing the hook over the platform, a cam having a dwell portion formed thereon, a roller carried by the chain for engaging the cam when the hook is positioned over the platform, a shaft for raising the platform when rotated, a clutch operably connected to the shaft and the cam for transmitting power from the cam to the shaft, whereby the platform is raised when the cam is struck and raises a reel carried by the hook from the hook, said roller serving to maintain engagement with the dwell portion of the cam until the hook has been advanced out of contact with the reel and then moving out of engagement with the cam, whereby the reel forces the platform downwardly, a storage ramp, a stop for engaging one edge of the platform to tilt the platform as it is forced downwardly, whereby the reel is discharged from the platform into the ramp, a rider pivotally mounted over the ramp, and means for connecting the rider to the clutch, said rider being merely rocked without moving the rider-connecting means when the ramp is not full and the rider is engaged by a reel rolling thereunder, but serving to actuate the rider-connecting means to disengage the clutch when engaged by two reels.

4. A conveyer, which comprises means for conveying articles along a predetermined path, an article-storing means, means for discharging articles from the conveying means into the article-storing means, means for actuating the article-discharging means, raisable means mounted above the article-storing means for preventing operation of the actuating means when raised, and a rocker mounted on the raisable means in such a position that the rocker is only pivoted and the raisable means is not raised when the rocker is engaged by a single article and the rocker is raised and the raisable means is raised when the rocker is engaged simultaneously by two articles.

5. A conveyer, which comprises means for conveying articles along a predetermined path, a ramp, means for discharging articles from the conveying means onto the ramp, means including a clutch for actuating the article-discharging means, raisable means mounted above the ramp for disengaging the clutch when raised, and a rocker mounted pivotally on the raisable means in such a position above the ramp that the rocker is only pivoted when engaged by a single article and raises the raisable means when engaged simultaneously by two articles.
